[57] CLAIM

The ornamental design for an enclosure handle, as shown and described.

DESCRIPTION

FIG. 1 shows a perspective view of an enclosure handle according to the principles of the present invention;

FIG. 2 shows a perspective view of the enclosure handle shown in FIG. 1 with the handle member in an open position;

FIG. 3 shows a right side elevational view of the enclosure handle shown in FIG. 1, a left side elevational view not being shown as it is a mirror image of the right side elevational view;

FIG. 4 shows a front elevational view of the enclosure handle shown in FIG. 1;

FIG. 5 shows a bottom end view of the enclosure handle shown in FIG. 1; and,

FIG. 6 shows a top end view of the enclosure handle shown in FIG. 1.
